UNITED STATES PATENT OFFICE

GEORGE A. BELL AND JOHN H. CARSON, OF MARION, INDIANA, ASSIGNEES TO INDIANA
FIBRE PRODUCTS COMPANY, OF MARION, INDIANA, A CORPORATION

FIBER-DISH MACHINE

Application filed March 8, 1926. Serial No. 93,352.

This invention pertains to a paper pie plate or dish making machine.

The object of the invention is to provide a machine wherein the stock in the form of an endless paper sheet is automatically and periodically fed into the machine, from which the blanks are cut, after which they drop into position to be stamped by a suitable die for dishing them and then drop onto a conveyor belt which conveys the completed article from the machine.

One feature of the invention resides in the automatic means for feeding the paper into the machine whereby it will be fed to the proper extent and then stopped sufficiently long for the shears to cut out the proper blanks.

Another feature of the invention resides in the arrangement of the shears whereby they are staggered with relation to each other so as to eliminate any waste stock, and are provided with means for overcoming the usual vacuum and forcing the blank from the shears so it will readily drop into position to be stamped into shape.

Another feature of the invention resides in the mechanism for operating the dies and the means for feeding the paper blanks thereto and discharging them therefrom onto a conveyor belt, the paper stock being properly heated by the dies so that they can readily conform to the shaping thereof.

Other features of the invention will be hereinafter more fully set forth and described.

The full nature of the invention will be understood from the accompanying drawings and the following description and claims.

Fig. 1 is a front elevation of the machine. Fig. 2 is the same as Fig. 1 showing parts thereof removed so as to illustrate the positioning of the shears and dies and the means for guiding the blanks from the shears to the dies. Fig. 3 is a side elevation of the machine illustrating its position at the time that the paper is being fed to the shears and the blanks are being formed by the dies. Fig. 4 is the same as Fig. 3 showing the position of the machine upon the feeding of the paper being stopped, the shears operating to cut the blank and the dies being in position to

receive the blank. Fig. 5 is a section taken on the line 5—5 of Fig. 1 illustrating the relative position of the dies and shears. Fig. 6 is the same as Fig. 5 illustrating the position of the machine after the shears have cut the stock, the dies being shown in operative position for dishing the blank. Fig. 7 is a detailed view showing the feeding mechanism. Fig. 8 is a detailed view showing the blank supporting mechanism. Fig. 9 is a detailed view showing the male devices and actuating mechanism therefor taken on the line 9—9 of Fig. 1.

In the drawings there is shown a machine having side frames 10 with a power drive 65 pulley 11 which is keyed to the shaft 12, said shaft being rotatably mounted in suitable bearings in the side frames 10. Between the side frames there is a substantially vertically mounted face plate 13 which is provided with 70 staggered circular openings 14 for receiving the shearing plungers 15, whereby a circular blank will be cut from the stock upon the shear being forced into said opening. As will be noted herein, the circular shears with 75 their respective openings are positioned in staggered relation on the face of the machine and so spaced with respect to each other that all available stock will be used in the cutting process, i. e., cutting of the stock being staggered in the usual manner which would not be possible if the shears were in the same horizontal plane.

The paper stock 16 is pulled off of the usual roll or heating and moistening table and onto 85 the table 17. The stock being normally curly, due to having been contained in the roll, is straightened by means of a plurality of rollers 17^a, 17^b and 17^c. Roller 17^a is stationary as well as the roller 17^c, whereas the roller 17^b is mounted on a lever 17^d, which is pivotally mounted on the frame at 17^e, the opposite ends of the lever 17^d being connected with an arm 17^f which is adjustably supported by a bracket 17^g, whereby the position of the roller 17^b with respect to the rollers 17^a and 17^c will cause the paper to pass around the bend for taking the curl therefrom and straightening it. The stock then passes between the roller 18 and feed roller 19. The roller 19 is mount- 100

ed on the shaft 20 upon which the control ratchet 21 is keyed having the ratchet teeth 22, there being shown herein three sets of teeth. Pivotally mounted on the shaft 20 there is a bell crank lever 23 having a spring actuated pawl 24 adapted to engage said teeth, the opposite end of the bell crank lever 23 being pivotally connected with the link 25 which in turn is connected to the upper end 10 of the arm 26. The lower end of said arm is pivotally mounted on the shaft 27. Between the ends of the arm there is a projecting portion having a cam engaging roller 28 in position to be engaged and operated by the cam 29 keyed to the shaft 12. By means of this arrangement, as the shaft 12 is rotated the cam 29 will cause such action with the pawl 24 as to rotate the shaft 20 one-third revolution and feed that amount of stock in the machine which is equal to one-third of the periphery of the feed roller 19, or slightly more than the diameter of the blank to be cut. Thereafter the feeding of the paper will be arrested while the pawl 24 is brought into engagement with the succeeding ratchet tooth so as to give ample time for the shears to operate for cutting the blank.

The shears 15 are mounted on their respective cutting blocks 30 which in turn are secured to a common carrying block 31 slidably mounted in the frame 32. The block 31 is connected with the rod 33 through the rearwardly extending projection 34. The rod 33 extends across the machine from one side to the other, having its ends supported in the sliding plates 34 and connected with the arm 35, the projection 34 being slidable in the fixed guides 36 mounted on each side of the machine. The forward end of the arm 35 is enlarged so as to embrace the cam 37 which is keyed to the shaft 12. By reason of this arrangement, upon rotation of the shaft 12, the sliding block 31 is reciprocated in its frame 32 and the shears 15 are caused to move forwardly into the openings 14 of the plate 13. As will be noted in Figs. 5 and 6 the paper passing in between the rear surface of the plate 13 and the shears will have circular blanks cut therefrom, the scrap falling downwardly and deflecting rearwardly so as to be discharged from the machine.

Upon the blanks being cut by the reciprocating cutting action of the shears, in order to overcome the vacuum and prevent the paper from being drawn back through the dies so that the blanks will drop in their respective guides, there is a plunger 41 mounted in the face of each shear so as to seat therein and not engage the paper ahead 55 of the cutting action of the shears, but upon the return of the shear from cutting action will be caused to move outwardly with respect to the shear and retain a fixed position with respect to the face plate 13, where 60 by the blanks will be prevented from re-

turning with the shear and will drop by gravity along the forward or front surface of the face plate 13. The mechanism for actuating the plungers 41 comprise the stem 42 upon which the plunger is mounted, which extends rearwardly through the blocks 31 and 30 so as to be slidable therein. Said stem has a head 43 and a compression spring 44 surrounding the same between the head and block 31 whereby it will normally be maintained in closed position as shown in Fig. 5. The block 31 carries a plurality of rearwardly extending ears 45 upon each of which there is a fulcrumed arm 46. The arms 46 are each provided with a head 47 in position to engage the respective heads 43 of the pins 42. The opposite ends of the arms 46 are pivotally connected with their respective rods 48 which are securely anchored to the frame of the machine. It will be noted that in normal position the spring 44 will maintain the plunger 41 seated in the shear. Said plunger will remain seated therein as the shear is moved outwardly so as to cut the stock. Upon the shear reaching its furthermost movement, the plunger, by reason of the action of the fulcrumed arm 46, will be forced outwardly from the face thereof against the severed blank so as to completely separate it from the shear, break the vacuum and permit it to drop down on the outside of the face plate, as shown in Fig. 6.

Mounted on the front of the face plate 13 there are a plurality of guide flanges 50 arranged in vertical position for guiding the blanks downwardly after they are cut, into position to be received by the die. Properly positioned at the lower end of the flanges 50 and intermediate the same there are a plurality of stop pins 51 slidably extending through a suitable opening in the face plate for engaging and arresting the downward movement of the severed blanks 52. The upper stop pins 51 extend through the face plate directly above the die block and the lower stop pins 53 extend therethrough immediately below said die block. The pins 51 and 53 are slidably mounted in a suitable framework 54 and are connected with the lever 55 having an arm 56 connected to and actuated by the rod 57 which in turn is connected with the lever 58 fulcrumed on the side of the machine at 59 and having its opposite ends provided with a roller 60 movable in the cam 61 which is mounted on the shaft 12. (See Figs. 1 and 8). By means of this arrangement, when the upper pins 51 are moved forwardly they arrest and hold the blank 52 while the preceding blank is being stamped. Upon discharge of the preceding blank from the die, the upper pin is retracted and the lower pin is moved forward so that the blank 52 will drop down into position on the lower pin and be held 130

in proper position for stamping by the die. Surrounding the plungers and intermediate thereof and behind the face plate 13 there is a stripper plate 13^a, which in normal position lies flush with the face of the plungers 15. Said plate is supported in connection with the blocks 30 and 31 by a plurality of springs 13^b. Said stripper plate is resiliently forced against the remainder 10 of the sheet after the blanks have been punched therefrom for pushing scrap paper forward from around the punches and supporting it in position during the shearing or punching action, as shown in Fig. 6, but 15 relieving the same, as shown in Fig. 5, for permitting the sheet to pass on through the machine. The springs 13^b are employed to compensate for sheets of varying thickness, whereby variations of thickness of said 20 sheets will not affect the punching action of the sheets or plungers. The spring mounting of the stripper plate will in the same manner accomplish this for multiple sheets, wherein it may be desired to pass 25 the same through a machine simultaneously.

Mounted below the face plate 13 and in alignment therewith there are female die blocks 60 secured upon the frame 54, said female blocks being so shaped as to receive 30 and permit the blank to be dished therein. The male die blocks 61 are mounted in pairs, as shown in Fig. 9, and are supported on the sliding frame 62 slidably mounted in the side frame 63 which is rigidly secured to 35 the machine. Each die block has a rearwardly extending stud 64 about which the compression spring 65 extends, said spring being mounted between the cross frame 62 and the bar 66 which is slidably mounted 40 on the stud. The bar 66, intermediate each of the studs for the respective pair of dies is provided with a depression for receiving the lower end of the rocker arm 67 so that wherein the lower end of the rocker arm is 45 forced forwardly through the medium of the cross bar 66, the male die will be brought into engagement with the female die by reason of the pressure exerted upon the compression spring 65. This will act to equalize 50 the movement and action of the dies so that no undue strain will be imparted thereto.

The rocker arm 67 is fulcrumed on the shaft 27, and at its upper end is provided 55 with a roller 68 adapted to engage the cam 69 which is keyed to the shaft 12. The movement of the rocker arm is so timed that it will cause the dies to engage and press the blank into dish shape at the same time that 60 the shears operate to cut a set of new blanks whereby the operation of the machine is continuous. There are illustrated herein 65 four shears and four dies, the guide plate 50 guiding the blanks cut by each of the shears to their respective dies, there being

always some of blanks indicated at 52 waiting to be received by the die after the finished dish 70 has been stamped and discharged therefrom onto the conveyor belt 71.

That portion of the machine immediately 70 forward of the dies, as shown in Figs. 3 and 4, is provided with a cross bar 72 extending the full width of the machine, through which there are slidably mounted a plurality of pins 73, the forward ends of said 75 pins being connected with the sliding frame 62. Intermediate the cross bar 72 and the head 74 of each of said pins there is a heavy compression spring 75 which acts to return the male dies after having been actuated by 80 the rocker arm 67.

It is essential that the dies be heated so as to impart heat to the stock being stamped therein, and to that end there are provided suitable gas burners 76 positioned to throw 85 flames on the backs of the female and male dies for heating the same. However, as it is detrimental to have the heat applied to the dies carried to the shears because of the expansion and contraction thereof, the die support frame 54 is provided with a water cooling jacket 77. This prevents the greater portion of heat from passing to that portion of the frame carrying the shears. 90

As shown in Fig. 1, the shaft 20 upon which the paper feed roll 19 is mounted, is provided with a brake drum 80 of the usual character, about which the brake band 81 is mounted so as to exert a constant friction resistance to the movement of the shaft 95 which may be overcome only by the actuation of the pawl 24 upon the ratchet wheel 21. This will cause the feeding of the paper to be instantly arrested and held against further movement upon the stopping of the forward movement of the pawl. Thus there will be no free play or coasting of the feeding apparatus and accordingly a more positive action. 105

The invention claimed is: 110

1. A machine of the character described including means for feeding a paper strip into the machine, a plurality of blank cutting shears positioned in staggered relation to each other on said machine, a forming die associated with and spaced from each of said shears, means for guiding the blanks cut by each of said shears to its respective die, and means for actuating said shears and dies in timed relation to each other. 115

2. A machine of the character described including means for feeding a paper strip into the machine, a plurality of shears mounted in said machine for cutting a plurality of blanks from the paper strip, a shaping and forming die mounted in said machine associated with and spaced from each of said shears, means for causing the blank cut by each shear to pass to its respective die, and 125 130

means for operating said shears and dies in timed relation with each other.

3. A machine of the character described including means for feeding a paper strip into the machine, a plurality of shears for cutting blanks from said strip, said shears being formed in staggered relation with respect to each other so as to partially overlap and thereby minimize waste, a forming and shaping die on said machine associated with and spaced from each of said shears, means for causing the blanks to pass from the shears to their respective dies, and means for actuating said shears and dies in timed relation with each other.

4. A machine of the character described including a substantially vertical face plate, a plurality of shears mounted on said machine and associated with said face plate for cutting blanks from a paper strip fed therein, a forming and shaping die for each shear mounted below their respective shears in position to receive said blanks as they are dropped therefrom, means mounted on said face plate for guiding said blanks from the shears to their respective dies, and means for actuating said shears and dies in timed relation with each other.

5. A machine of the character described including a substantially vertical face plate, means for feeding a paper strip into said machine along the rear surface of said face plate, a plurality of shears mounted in the rear of said face plate in staggered relation to each other for cutting blanks from said paper and forcing said blanks through suitable openings in said face plate to the forward surface thereof, a die associated with said face plate for each of said shears and positioned below the same, a plurality of guide members for guiding the blanks down the forward surface of said face plate to their respective dies, and means for actuating said shears and dies in timed relation to each other.

6. A machine of the character described including means for feeding a paper strip into the machine, a blank cutting shear mounted on said machine, a female die for receiving a blank cut by said shear, means for actuating said shear and die in timed relation to each other, said die having a normally protruding plunger slidably mounted therein provided with a head seatable in the surface thereof, a male die having a plunger slidably therein and provided with a head normally projecting therefrom and seatable in the surface thereof, said plunger heads being so positioned as to receive and grip a blank therebetween and maintain it in position between the members of said die until they are operated to form and shape the same and thereafter to cause the formed blank to be ejected from the female die.

7. A machine of the character described in-

cluding means for feeding a paper strip into the machine, a blank cutting shear mounted on said machine, a female die for receiving a blank cut by said shear, means for actuating said shear and die in timed relation to each other, said die having a normally protruding plunger slidably mounted therein provided with a head seatable in the surface thereof, a male die having a plunger slidably therein and provided with a head normally projecting therefrom and seatable in the surface thereof, said plunger heads being so positioned as to receive and grip a blank therebetween and maintain it in position between the members of said die until they are operated to form and shape the same and thereafter to cause the formed blank to be ejected from the female die, and means associated with said die for supporting said blank in position to be gripped by said plungers when in one position, and when in the other position to support the incoming blank and hold it out of engagement therewith until the ejection of the preceding blank.

8. A machine of the character described including means for feeding a strip of paper into the machine, a blank cutting shear mounted on said machine for cutting blanks from said strip of paper, means for forming and shaping the blanks, a cam shaft, means for rotating said cam shaft, a cam on said shaft for actuating said cutting means, a rocker arm mounted on said machine for actuating said forming means, a cam on said cam shaft for actuating said rocker arm, means for controlling the intermittent feeding of the paper sheet to the machine whereby it will be arrested in its feeding during the cutting operation thereof, and a cam on said cam shaft for controlling said feed control means whereby the feeding, cutting and forming means will be actuated in timed relation with each other.

9. A machine of the character described including means for feeding a paper sheet into the machine, a plurality of blank cutting shears mounted on said machine for cutting blanks therefrom, means associated with said blank cutting shears for receiving the blanks directly therefrom, shaping and forming the same, means for heating said shaping and forming means for assisting in the forming of the paper, and a water jacket positioned intermediate said shaping and forming means and said cutting means for preventing the greater part of the heat from reaching said cutting means.

10. A machine of the character described including means for feeding a paper strip into the machine, a plurality of cutting shears positioned in staggered relation to each other for cutting blanks from the sheet of material and permitting them to drop therefrom, a forming and shaping die mounted on said machine for each of said shears and posi-

- tioned below the same for receiving the paper blanks dropped therefrom, guide members mounted on said machine for guiding the blanks from the shears to their respective dies, means associated with said dies for receiving and positioning the blanks preparatory to being pressed therein, and means for actuating said shears and dies in timed relation with each other.
11. A machine of the character described including means for feeding a paper strip into the machine, a plurality of blank cutting shears mounted on said machine, means for actuating said shears for cutting blanks from said strip, a forming die associated with and spaced below each of said shears, and a plurality of trough-like guides connecting said dies with their respective shears for guiding the blanks cut by said shears to their associated dies.
12. A machine of the character described including a substantially vertical face plate, a plurality of shears mounted on said machine and associated with said face plate for cutting blanks from a paper strip fed therein, a forming and shaping die for each shear mounted below their respective shears in position to receive said blanks as they are dropped therefrom, means for guiding said blanks to their respective dies, and means for supporting said blanks and withholding them from their respective dies until the blank being formed therein has been discharged.
13. A machine of the character described including a substantially vertical face plate, a plurality of shears mounted on said machine and associated with said face plate for cutting blanks from a paper strip fed therein, a forming and shaping die for each shear mounted below their respective shears in position to receive said blanks as they are dropped therefrom, means for guiding said blanks to their respective dies, and means for supporting said blank in position to be engaged and formed by its respective die when in one position, and when in another position permit the formed blank to be discharged therefrom while supporting and withholding from said die the next succeeding blank.
14. A machine of the character described including means for feeding a paper strip into the machine, a plurality of blank cutting shears mounted on said machine in position to engage and cut blanks from said strip, a plurality of forming dies associated therewith for engaging and forming said blanks, means for discharging said formed blanks therefrom, and means associated with said feeding means for engaging and bending the paper strip and causing it to pass out of line with said cutting shears and dies whereby the normal curl of the strip will be removed so as to permit it to enter said machine and be engaged by said dies in a substantially flattened condition.
15. A machine of the character described including means for feeding a paper strip into the machine, a plurality of blank cutting shears positioned on said machine adapted to engage and cut blanks from said strip, a plurality of forming dies associated with said shears for receiving said blanks and forming the same, a plurality of rollers adapted to engage said sheet, means adapted to engage one of said rollers for causing the same to bend the paper out of line with said shears whereby the normal curl of the paper will be removed therefrom so as to permit it to enter the machine and be engaged by said shears in a substantially flattened condition.
- In witness whereof, we have hereunto affixed our signatures.
